UNITED STATES PATENT OFFICE.

QUINCY A. FISK, OF SPRINGFIELD, ILLINOIS.

APPARATUS FOR TRANSPORTING AND DUMPING EARTH, GRAVEL, &c.

SPECIFICATION forming part of Letters Patent No. 291,587, dated January 8, 1884.

Application filed May 26, 1883. (No model.)

To all whom it may concern:

Be it known that I, QUINCY A. FISK, a citizen of the United States, residing at Springfield, in the county of Sangamon and State of Illinois, have invented a new and useful Apparatus for Transporting and Dumping Earth, Gravel, &c., of which the following is a specification, reference being had to the accompanying drawings.

10 This invention relates to apparatus for transporting and dumping earth, gravel, &c., of that class in which an elevated cable-way is arranged, on which the transporting-cars are adapted to slide from the point of loading to the point of deposit.

15 The object of my invention is to provide simple, durable, inexpensive, and efficient means whereby the whole operation of running, returning, and dumping the cars will be automatically effected.

20 In the drawings, Figure 1 is a plan view of my improved apparatus in position for operation. Fig. 2 is a side view of the same. Fig. 3 is a vertical longitudinally-disposed sectional view on the line *x x*, Fig. 1. Fig. 4 is a vertical transverse sectional view taken through one of the cars on the line *y y*, Fig. 1.

25 Referring to the drawings, A designates the elevated cable on which the cars are adapted to run. This cable is anchored to a post, B, or other suitable device arranged at the loading end of the apparatus, and from this post the ends C C of the cable diverge to the ends of a cross-bar, D, from which they extend to the ends of another cross-bar, E, that is arranged at the dumping end of the cable-way, and again converge so as to pass around a pulley, F, journaled in a block, G, all as shown. The cable preferably passes through perforations H in the ends of the bars D and E, and by this arrangement two independent cable-ways, I I, are formed, each extending between the correspondingly-opposite ends of the said bars D and E and at one side of the apparatus. 30 The pulley-block G is provided with a screw-threaded stem, J, that passes through a screw-threaded eye, K, in one end of a swivel-loop, L, by operating which the cable can be tightened or stretched, as desired. This swivel L is provided with a swiveled hook or eye, M, by which it may be anchored to a stake or other suitable device, N, arranged at the dumping end of the apparatus. The cross-bar D at the loading end of the cable-way is supported in stationary or fixed position on a suitable horse 35 or frame, O, while the other cross-bar, E, is held in a plane somewhat lower than the plane of the bar D by being swiveled on the end of a rod, P, that projects from the block G, and is supported by a horse or frame, Q, as shown. 40 By reason of a swivel or pivotal connection, R, with the end of the bar or rod P, the cross-bar E can swing so that its ends will play vertically.

45 S S designate suitable cars, each of which is adapted to run back and forth on one of the cable-ways I at one side of the apparatus. One of these cars will be at the dumping end of its cable-way I, while the other car will be at the loading end of its cable-way, and the 50 cars are connected by a rope or cable, T, which is endless, and passes around pulleys U, that are journaled at the ends of the cross-bars D and E. When the car at the loading end of the apparatus is loaded and released, it will 55 slide down its cable to the dumping end of the apparatus. During this movement of the car the weight of its contents will cause the cross-bar E to turn on its pivot, with its end at the side of the loaded car down and with its other 60 end consequently thrown up, so that the cable at that side the apparatus will then be on the same horizontal plane its entire length, or will even incline a little from the dumping end. 65 This position of the said cable will render it 70 easy for the car which was at the dumping end of the apparatus to return to the loading end as the loaded car passes to the dumping end, and by reason of the endless rope T the said 75 empty car will be carried back by the loaded 80 car. This operation, it will be observed, is 85 entirely automatic, as the loaded cars will automatically slide down the inclined cable and will automatically return the just emptied car to the loading end again. The cars may be 90 mainly of any suitable construction, and are 95 pendent from suitable brackets, V V, carrying grooved rollers W, that run on the cable. Each cable I is provided with a sliding collar, X, arranged at the dumping end of the appa- 100 ratus, and provided with a set-screw, Y, by which it may be secured in the desired posi-

tion. The cars will come against these collars, which thereby serve to limit their movement down the cable.

When the cars are to be used for transporting earth, sand, gravel, and the like, they are provided with a bottom, Z, inclined from its center, and with hinged sides A² A², having loops B² projecting from their bottom edges. These loops are engaged by the hook-shaped ends C² C² of a transverse latch-rod, D², which is adapted to slide vertically in suitable guides, E², depending from the under side of the car. When this rod D² is down, it will engage the loops and hold the sides of the car closed; but when the said rod is lifted it will release the loops and enable the sides to be opened by the weight of the load and deposit the latter. To effect the automatic operation of the rod, it is operated by a longitudinal bar, F², that is pivoted at one end of the car, as shown at G², and serves to support the rod D². The free end of the bar F² is connected by a chain or rope, H², with a bell-crank lever, I², fulcrumed in a bracket, J², projecting from the top of the car. The top of this lever is provided with a recess or eye, K², to accommodate the cable, so that the lever is thrown back when it comes against the collar on the latter, which lifts the rod F² and causes the latch-rod D² to be elevated. At the loading end of the apparatus are provided pivoted rods L² L², having hook-levers M², adapted to engage loops N² on the end of the car, to hold the same while it is being loaded.

The operation and advantages of my invention will be readily understood. It is very simple and convenient in operation, and by reason of the pivoted or tilting bar at the dump end of the apparatus a greater incline is given to the loaded car to run to the dumping end, while the other cable is inclined toward the loading end to provide an incline for the return of the empty car to the loading end.

It is evident that my improved cable apparatus can be used for the transportation of matter which it is not desired to dump, in which instance the construction of the cars is varied to suit.

Under some circumstances the apparatus may be used as a passenger conveyance for children, &c., and in this case I prefer to plant the cable on a level plane and then operate both loaded cars by simply lifting the ends of the pivoted bar alternately.

I claim as my invention—

1. The combination of an elevated stationary or fixed horizontal bar disposed transversely at one end of the way, a transverse horizontally-disposed bar arranged at the other end of the way, and pivoted or swiveled at its center, the elevated cable connected to the ends of these end bars, and extending longitudinally, suitable transporting-cars arranged to run back and forth on their cables and serve to alternately tilt the pivoted bar, and an endless connecting-cord extending around the cable-way, and secured to the cars, so that they will be at different ends of the way, as and for the purpose set forth.

2. An elevated cable-way comprising a transverse horizontal fixed bar at one end, a swiveled pulley-block anchored at the other end of the way, and provided with a projecting bar supported upon a suitable horse or frame, a horizontally-disposed transverse bar pivoted on the end of this projecting bar, the cable anchored at the end of the way having the stationary bar, and diverging from the anchoring point to the ends of the said bar, from which it extends down at both sides of the way, and is secured to the swiveled block, suitable transporting-cars arranged to run on the cables, and a connecting-rope secured to the cars, and having bearings around pulleys at each end of the cable-way, as and for the purpose set forth.

3. The combination, with the elevated cable having an adjustable collar, of the dumping-car hung from brackets carrying rollers by which it runs on the cable, and provided with an inclined bottom, hinged sides having the loops, the transverse latch-bar having ends that engage the said loops, and arranged to slide vertically in guides projecting from the under side of the car, the longitudinal operating bar pivoted at one end, and the bell-crank lever arranged to be operated by the adjustable collar, and connected with the longitudinal bar by a chain or rope, as and for the purpose set forth.

In testimony that I claim the foregoing as my own I have hereto affixed my signature in presence of two witnesses.

QUINCY A. FISK.
